UNITED STATES PATENT OFFICE

FREDERICK KLEIN, OF COLLEGE POINT, NEW YORK, ASSIGNOR TO WARP TWISTING-IN MACHINE COMPANY, OF BROOKLYN, NEW YORK, A CORPORATION OF NEW YORK

MECHANISM FOR KNOTTING TOGETHER STRANDS

Application filed May 29, 1930. Serial No. 457,431.

This invention relates to mechanism for uniting threads or other strands by a knot and particularly by that simple form of knot in which the two end portions of the strands, 5 projecting in the same direction, extend around the strands to form a loop and then through the loop. In general, the object is to provide a reliable and efficient mechanism for tying strands together however fine in 10 quality the strands may happen to be. More specifically, the object is to provide a mechanism for tying knots which may be used in the stead of the twisting mechanism of a machine for uniting warp threads of the class 15 represented by United States Letters Patent No. 1,690,157 and those therein mentioned and in cooperation with the other instrumentalities of such a machine concerned in the selection and proper feeding of the 20 strands or threads of the two warps (old and new) successively from such warps, it being recognized that certain strands cannot be twisted together properly and must be united by knotting, as those characterizing the fabric 25 known as "Georgette", or any other textile where tightly twisted yarn is used.

In the drawings,

Fig. 1 is a side elevation of a machine embodying the improved knot-tying mechanism and, with certain guides 5 of a fork 2 shown in other views, instrumentalities for supporting the warp, old and new, and selecting and advancing therefrom the strands to be united by said mechanism;

Fig. 1a is a front elevation of the same, and of the beams for the two warps;

Fig. 2 is a front elevation and Fig. 3 a plan of said mechanism;

Fig. 4 is a section on line 4—4, Fig. 3;

Fig. 5 is a front-to-rear vertical sectional view substantially coincident with spindle 19 in Fig. 2;

Figs. 6, 7, 8, 9, 10, 11 and 12 are rear elevations of the knot-tying instrumentalities at successive stage in a cycle of the tying operation;

Figs. 6a, 7a, 8a, 9a, 10a, 11a and 12a are views respectively corresponding to Figs. 6 50 to 12, inclusive, but showing the parts in side

elevation, except for the part 19—20, which is in section; and

Fig. 13 is a transverse sectional view of the three tying blades on line 13—13, Fig. 6a.

When, as in accordance with my specific object, a machine embodying my knotting mechanism is employed like that shown in Fig. 1, the two warps (old and new) will be suspended from clamping means 1, extending subject in any way to suitable tension 55 down between the members of a fork 2 and then in opposite directions to their supply beams A (Fig. 1a), and the strands, released in pairs (one from each warp) successively by the means 3, will by the (spiral) means 4 60 be successively fed forward, being delivered a pair at a time to the hooked guides 5 formed as the terminals of said fork, the fork receiving reciprocation from the cam 7 geared with the shaft of the means 4, all as in the 65 patents mentioned. My mechanism is incorporated in the place of the fixed and rotating members of the twisting means of the mentioned patents, to wit, it is supported by the fixed shaft 8 and the rotating shaft 9 geared 70 with the shaft of means 4 as shown at 10, shaft 9 also affording the medium for driving certain elements which actuate moving parts of the knotting mechanism as will appear. 75 11a is a stationary fork which steadies the two strands when advanced and delivered to the knotting mechanism by the guides 5 of fork 2.

The frame of the knotting mechanism includes as its principal parts the frame proper 85 11 (fixed to shaft 8 and having a bearing support on shaft 9), a bracket 12, secured to the front of the frame proper by screws 13 and having a dished apertured and forwardly reaching seat 14, and a tubular bearing member 15 having an annular enlargement or housing 16 formed with a convex periphery (which engages in the concave side of the seat and is held therein by a screw 17 and dished washer 17a) said bearing member 15 projecting through a hole 11a, Fig. 4, in the frame proper. In bearing member 15 is journaled the body or spindle 19 of the tying bill, the same being confined against endwise movement by a head 20 on its rear end and 95 100

a pinion 21 secured on its front portion with in housing 16. The pinion is in mesh with a gear 22 on shaft 9 and since the axis of the tying bill body or spindle is inclined downwardly and forwardly as shown the teeth of the pinion are bias-cut; the gear-ratio of the pinion and gear is 2-1.

The tying bill includes three blades in laminated relation and arranged eccentrically of the spindle 19, the intermediate blade 23, which is longitudinally movable, having a long shank reaching through and protruding from the front of spindle 19 and the other two, 24 and 25, having T-shaped shanks the cross-arms of which are held in a cross-cut 26 in the head 20 of said spindle by a split disk 27 secured to said head by screws 28 and slotted to receive all three blades. The blades have side-by-side jaws at their rear ends which form what I term the gripper of the bill. The jaw of blade 23 has at its forward margin on one side a shearing and on the other side a rounded or gripping edge; the jaw of blade 24 has at its rear margin and on the side next to blade 23 a shearing edge to coat with the shearing edge of that blade; and the jaw of blade 25 a rounded gripping edge to coat with the gripping edge of that blade—see Figs. 13 and 6a to 12a. Blade 23 has at its rear margin a shoulder 23a, and blade 24 a hook or horn 24a projecting oppositely to the mentioned jaws of all three blades (and giving it and in fact the bill as a whole an anchor-like form), the purposes of which will appear. When the blade 23 is shifted rearward it forms a crotch 29 (Fig. 10a) to receive the two strands, *a* and *b*, and when it is shifted forward such strands will be first gripped by the two coacting gripping edges and then severed by the two coacting shearing edges of the blade jaws, such gripping and severing, with ends of the strands left gripped by the jaws of blades 23-25 until the bill is opened by the ensuing rearward shifting of blade 23, being in itself known; when the jaw 23 is forward and the gripper is closed the gripper tapers to substantially a point.

The shifting of blade 23 is obtained from a cam 30 on shaft 9 through a lever 31 fulcrumed in bracket 32 affixed to the housing 16 of bearing member 15 and thus forming part of the frame and pivoted to a ring 33 engaged in a groove 34 of a collar 35 in effect splined to spindle 19 by the pin 36 engaging a slot in the spindle as shown in Fig. 5, said pin penetrating the blade and so coupling it to the collar. Thus while the tying bill is being rotated the blade 23 is reciprocated relatively to blades 24-25.

Since in the first part of a tying operation—to wit, until the two strands become held by the bill itself—the guides 5 must remain holding the strands it is necessary that the head of the bill formed by the gripper

and hook 24a should rotate in an orbit around the guides; hence the arrangement of the blade-group so that they are eccentrically related to the spindle. In the rotation the gripper leads and the hook 24a follows—see Figs. 6-12. As will appear, the gripper passes rearward of the upstanding portions of the strands and forward of their horizontal portions; as for the horn or hook 24a it passes forward of all portions of the strands. To accomplish this the spindle 19 is inclined downward and rearward and the apex of the gripper is arranged to travel in an orbit in a plane *p*—*p*, Fig. 6a, which cuts the (here vertical) plane occupied by the horizontal and vertical portions of the strands above their horizontal portions and lies forward of them and the apex of the hook 24a is arranged to travel in an orbit parallel with plane *p*—*p* and wholly forward of all said strand portions.

It is preferable to provide a strand-retainer, as 37 here shown attached to the frame proper 11 and projecting rearwardly so as to receive in its notch shown (Figs. 5 and 6) strand *a* when the strands have been advanced as described into the control of the hooks of guides 5.

38 is a knot-tightening arm fixed to and rotating with shaft 9 and having its end bifurcated as shown in Fig. 3 so that when it approaches the position for tightening the knot (as will appear), is forked end 38a then moving down toward strand *b*, such end will straddle the then upright anchor-shaped head of the knotting bill.

Operation: The starting position of the bill in a cycle of its operation (two revolutions thereof to one of shaft 9) is that shown in Figs. 5 and 6-6a, where the gripper thereof projects upwardly; during the preceding half-revolution, while the bill blades were more or less horizontal, the two strands *a* and *b* were advanced by the means 4 and left caught by the hooks of guides 5 and then, incident to the action of means 7, carried forward by these guides so that their upstanding portions are placed forward or inward of the orbit *pp* of the bill gripper when it reaches said starting position, the horizontal portion of strand *a* being, however, rearward or outward of said orbit. In Figs. 7-7a the bill has turned a quarter-revolution, its gripper rearwardly clearing said upstanding portions of the strands. At the half-revolution stage, Figs. 8-8a, the shank portion of the bill proper, formed by the shanks of its blades, has forced said portions aside and formed in the strands a bend *x*, the free end of the gripper having passed down forward of the horizontal portion of strand *b* and the gripper camming this portion back. At the three-quarters revolution Figs. 9-9a, the horn 24 acting as a strand deflector (and as to those orbit the divergent as well as upstand-

ing portions of the strands are rearward or outward) has cammed the upstanding portions of the strands back and the gripper has begun to cam back the horizontal portion of strand *a* and the operation has reached the inception of the formation of a loop *y* (Fig. 10) around the gripper, the guides 5 having now receded from the strands. At the completion of the first revolution, Figs. 10-10a, this loop *y* is completed; it is held from slipping off the tapered gripper, whose apex now projects upwardly, by the shoulder 23a blade 23 having been moved rearward so that the gripper is open. At the fifth quarter revolution stage Figs. 11-11a the open gripper has received the upstanding portions of the strands (it being noted that the forming of the loop around the gripper has diverted the upstanding portions of the strands from the vertical). At the sixth-quarter stage, Figs. 12-12a, the gripper has closed and gripped the strands and severed them, remaining gripping the severed ends of the horizontal portions of the strands (the upstanding portions falling away free) while the arm 38 descends upon both strands and by depressing them constricts the loop, as by the downward pressure and the taper of the (closed) bill it slips off the latter onto the still gripped end portions of the strand, into a tightened or completed knot *z*. In the next half-revolution the bill opens to release the united strands preparatory to the next cycle of operation on the succeeding pair of strands.

The uniting of strands by a knot such as is formed by the present mechanism, using a tying bill having a gripper rotating in an orbital path, is not new where the portions of the strand manipulated by the bill lie entirely side by side. My invention distinguishes from this in that it includes means (as 1-5-A) which holds the strands so that they stand in part side by side and then diverge in substantially opposite directions and that the gripper of the bill in a revolution passes outward of the side-by-side portions and inward of the diverging portions of the strands. In the actual embodiment this results from the orbital path of the gripper being in a plane obliquely related to that of the strands, such as the plane *p-p* referred to. My invention further distinguishes from any previous tying mechanism of which I am aware in that the tying means itself (here formed by the bill blades 23, 24, 25) and not merely its gripper travels in an orbital path, because of its arrangement eccentrically in the rotary spindle 19. At the outset of a tying operation the guides 5, acting as means to hold the strands in reach of the bill, are flanked by it, and in order to act on the strands to tie the knot the bill moves in the said orbital path, or around the guides.

So far as is concerned the transfer of the strands from the means 5 to the knotting means (bill) it is obviously not broadly material which of them moves toward the other to permit the transfer.

As hereinbefore indicated, on forming the loop on the hereinbefore designated projecting part or gripper (or as it may be otherwise termed, the looper thereof) it is held against slipping off prematurely by the loop stop formed by shoulder 23a, which is then unsheathed with respect to the looper-components 24 and 25 but becomes sheathed thereby when blade 23 is later moved forward, thereby releasing the loop. So far as I am aware, a looper so constituted is new in this art.

When the strands are held taut (as usual) between the instrumentalities 1 and A it is necessary to cause movement of one or the other of them to relax each strand during the knotting so as not to rupture it, assuming of course that the strand can not stretch appreciably without breaking. Hence the clamp 1 is carried by a reciprocating structure 1a which has a cross-groove 1b in which plays a roller 1c on a disk 1d on the shaft of the cam 7, whereby on every reciprocation of the fork or revolution of shaft 9 the means 1 will descend to relax the strands.

Having thus fully described my invention what I claim is:

1. In combination, supporting means, a tying bill revoluble therein and having a strand gripper projecting angularly with respect to its axis of rotation, means to hold the strands to be knotted together so that they stand in part side by side and then diverge in approximately opposite directions, and means to rotate said bill and in a revolution thereof cause the gripper to pass outward of the side-by-side portions and then inward of both diverging portions of the strands, thus during such revolution to form a loop around the bill, said gripper being adapted on completion of the loop to grip said side-by-side portions, whereby on slipping of the loop off the free end of the gripper while it still holds said side-by-side portions a knot may be formed in the strands.

2. In combination, supporting means, a tying bill revoluble therein and having a strand gripper projecting angularly with respect to its axis of rotation and a strand deflector, means to hold the strands to be knotted together so that they stand in part side by side and then diverge in approximately opposite directions, and means to rotate said bill and in a revolution thereof cause the gripper to pass outward of the side-by-side portions and then inward of both diverging portions of the strands and the deflector to pass inward of both said side-by-side and diverging portions, thus during such revolution to form a loop around the gripper, said gripper

being adapted on completion of the loop to grip said side-by-side portions, whereby on slipping of the loop off the free end of the gripper while it still holds said side-by-side portions a knot may be formed in the strands.

3. In combination, supporting means, a tying bill revoluble therein and having a strand gripper projecting angularly with respect to its axis of rotation, and means to hold the strands to be knotted together so that they stand in part side by side, with their side-by-side portions relatively inward of the orbital path of the gripper, and then diverge in approximately opposite directions, with their diverging portions relatively outward of said path, thus during a revolution of the bill to form a loop around the same, said gripper being adapted on completion of the loop to grip said side-by-side portions, whereby on slipping of the loop off the free end of the gripper while it still holds said side-by-side portions a knot may be formed in the strands.

4. In combination, supporting means, a tying bill revoluble therein and having a strand gripper projecting angularly with respect to its axis of rotation and a strand deflector and means to hold the strands to be knotted together so that they stand in part side by side, with their side-by-side portions relatively inward of the orbital path of the gripper and outward of the orbital path of the deflector, and then diverge in approximately opposite directions, with their diverging portions relatively outward of both of said paths, thus during a revolution of the bill to form a loop around the gripper, said gripper being adapted on completion of the loop to grip the side-by-side portions, whereby on slipping of the loop off the free end of the gripper while it still holds said side-by-side portions a knot may be formed in the strands.

5. In combination, supporting means, a tying bill revoluble therein and having a strand gripper projecting angularly with respect to its axis of rotation, and means to hold the strands to be knotted together so that lengths thereof lie approximately in a given plane and they stand in part side by side and then diverge, said bill having its said axis arranged obliquely to said plane and so that the orbital path of the gripper is relatively outward of the side-by-side and inward of the diverging portions of said lengths, thus during a revolution of the bill to form a loop around the same, and said gripper being adapted on completion of the loop to grip said side-by-side portions, whereby on slipping of the loop off the free end of the gripper while it still holds said side-by-side portions a knot may be formed in the strands.

6. In combination, supporting means, a tying bill revoluble therein and having a strand gripper projecting angularly with respect to its axis of rotation, and means to

hold the strands to be knotted together so that lengths thereof lie approximately in a given plane and they stand in part side by side and then diverge, said bill having its said axis arranged obliquely to said plane and so that the orbital path of the gripper is relatively outward of the side-by-side and inward of the diverging portions of said lengths and also having a strand deflector projecting angularly to said axis and whose orbital path is inward of all said portions, thus during a revolution of the bill to form a loop around the gripper, and said gripper being adapted on completion of the loop to grip said side-by-side portions, whereby on slipping of the loop off the free end of the gripper while it still holds said side-by-side portions a knot may be formed in the strands.

7. Mechanism to form a knot in a strand including, in combination, supporting means, means therein to hold the strand to be knotted with a bend therein, a tying bill revoluble in the supporting means with its axis of rotation near the bend and extending through the plane thereof, said bill having a strand gripper projecting angularly with respect to the bill, and means to rotate the bill and in a revolution thereof cause the gripper to pass outward of one portion of the strand extending from the bend and then inward of the other such portion, thus during such revolution to form a loop around the bill, said gripper being adapted on completion of the loop to grip the first-named portion, whereby on slipping of the loop off the free end of the gripper while it still holds said first named portion a knot may be formed in the strand.

8. Mechanism to form a knot in a strand including, in combination, supporting means, means therein to hold the strand to be knotted with a bend therein, a tying bill revoluble in the supporting means with its axis of rotation near the bend and extending through the plane thereof, said bill having a strand gripper projecting angularly with respect to the bill and a strand deflector, and means to rotate the bill and in a revolution thereof cause the gripper to pass outward of one portion of the strand extending from its bend and then inward of the other such portion and the deflector to pass inward of both said portions, thus during such revolution to form a loop around the gripper, said gripper being adapted on completion of the loop to grip the first-named portion, whereby on slipping of the loop off the free end of the gripper while it still holds said first-named portion a knot may be formed in the strand.

9. Mechanism to form a knot in a strand including, in combination, supporting means, a tying bill revoluble therein and having a strand gripper projecting angularly with respect to its axis of rotation, and means to

- hold the strand to be knotted with a bend therein and with one portion of the strand extending from the bend inward and the other such portion outward of the orbital path of the gripper, thus during a revolution of the bill to form a loop around the bill, said gripper being adapted on completion of the loop to grip the first-named portion, whereby on slipping of the loop off the free end of the gripper while it still holds said first-named portion a knot may be formed 70 in the strand.
10. Mechanism to form a knot in a strand including, in combination, supporting means, a tying bill revoluble therein and having a strand gripper projecting angularly with respect to its axis of rotation and a strand deflector, and means to hold the strand to be knotted with a bend therein and with one 15 portion of the strand extending from the bend inward and the other such portion outward of the orbital path of the gripper and both said portions outward of the orbital path of the deflector, thus during a revolution 20 of the bill to form a loop around the gripper, said gripper being adapted on completion of the loop to grip the first-named portion, whereby on slipping of the loop off the free end of the gripper while it still holds said first-named portion a knot may be formed 25 in the strand.
11. Mechanism to form a knot in a strand including, in combination, supporting means, a tying bill revoluble therein and having a strand gripper projecting angularly with respect to its axis of rotation, and means to hold the strand to be knotted with a bend therein, said bill having its said axis arranged obliquely to the plane of said bend 30 and so that the orbital path of the gripper is relatively outward of one portion of the strand extending from the bend and inward of the other such portion, thus during a revolution of the bill to form a loop around the same, said gripper being adapted on completion of the loop to grip the first-named portion, whereby on slipping of the loop off the free end of the gripper while it still holds said first-named portion a knot may be 35 formed in the strand.
12. Mechanism to form a knot in a strand including, in combination, supporting means, a tying bill revoluble therein and having a strand gripper projecting angularly with respect to its axis of rotation and a strand deflector, and means to hold the strand to be knotted with a bend therein, said bill having its said axis arranged obliquely to the plane of said bend and so that the orbital path of 40 the gripper is relatively outward of one portion of the strand extending from the bend and inward of the other such portion and the orbital path of the deflector is inward of both said portions, thus during a revolution 45 of the bill to form a loop around the gripper,
- said gripper being adapted on completion of the loop to grip the first-named portion, whereby on slipping of the loop off the free end of the gripper while it still holds said first-named portion a knot may be formed 70 in the strand.
13. In combination, supporting structure, a knot-tying means revoluble therein, spaced instrumentalities holding extended a strand to be knotted, and strand-delivery means 75 maintaining a bend in the extended part of the strand, one of said means being movable toward the other substantially lengthwise of the axis of the tying means whereby to permit transfer of the strand from the first to 80 the second-named means.
14. In combination, supporting structure, a knot-tying means revoluble therein, spaced instrumentalities holding extended a strand to be knotted, and strand-delivery means 85 maintaining a bend in the extended part of the strand and movable toward the tying means substantially lengthwise of the axis of the latter whereby to permit transfer thereto of the strand. 90
15. In combination, supporting structure, spaced instrumentalities holding extended a strand to be knotted, strand delivery means maintaining a bend in the extended part of the strand, and knot-tying means revoluble 95 in a path around the first-named means and adapted to receive the strand therefrom.
16. In combination, supporting structure, spaced instrumentalities holding extended a strand to be knotted, strand delivery means 100 maintaining a bend in the extended part of the strand, and knot-tying means revoluble in a path around the first-named means and adapted to receive the strand therefrom, one of said means being movable from and toward the other substantially lengthwise of the axis of the tying means. 105
17. In combination, supporting structure, a knot-tying means revoluble therein, spaced instrumentalities holding extended the 110 strands to be knotted together, and strand delivery means maintaining opposite bends in the strands and such bends close together, one of said means being movable toward the other substantially lengthwise of the axis of the tying means whereby to permit transfer of the strands from the first to the second-named means. 115
18. In combination, supporting structure, a knot-tying means revoluble therein, spaced instrumentalities holding extended the 120 strands to be knotted together, and strand-delivery means maintaining opposite bends in the strands and such bends close together and movable toward the tying means substantially lengthwise of the axis of the latter whereby to permit transfer thereto of the strands. 125
19. In combination, supporting structure, spaced instrumentalities holding extended 130

the strands to be knotted together, strand-delivery means maintaining opposite bends in the strands and such bends close together, and knot-tying means revolute in a path around the first-named means and adapted to receive the strands therefrom.

20. In combination, supporting structure, spaced instrumentalities holding extended the strands to be knotted together, strand-delivery means maintaining opposite bends in the strands and such bends close together, and knot-tying means revolute in a path around the first-named means and adapted to receive the strands therefrom, one of said means being movable from and toward the other substantially lengthwise of the axis of the tying means.

21. In combination, supporting means, and tying means comprising a structure rotative in said supporting means and having a projection extending angularly of its axis of rotation, a member revolute with said structure and rectilinearly movable lengthwise of said axis and having a projection extending angularly of the latter and coactive with the first projection to receive and grip a strand, and means to reciprocate said member.

22. In combination, supporting means, and tying means comprising a structure rotative in said supporting means and having a projection extending angularly of its axis of rotation, a member revolute with said structure and rectilinearly movable lengthwise of said axis and having a projection extending angularly of the latter, said projections having edges coactive to shear a strand interposed between them, and means to reciprocate said member.

23. In combination, a supporting structure, and tying mechanism comprising a rotary member journaled in said structure, blades arranged in and revolute with said member and having portions projecting angularly with respect to the axis of said member and coactive to receive a strand, one blade being movable relatively to the other rectilinearly and lengthwise of said axis, and means to reciprocate the movable blade while rotating with said member.

24. In combination, supporting structure, and tying mechanism comprising a rotary member journaled in said structure, blades arranged in and revolute with said member and having portions projecting angularly with respect to the axis of said member and coactive to receive a strand, one blade being movable relatively to the other rectilinearly and lengthwise of said axis, a collar slidable lengthwise on said member, means, affording a spline-connection between the collar and said member, to connect the collar with the movable blade, and means to reciprocate the collar while said member is rotating.

25. A revolute tying bill of the class described having a strand looper projecting

angularly with respect to its axis of rotation, said bill comprising parts forming the looper and one of which has a projecting loop stop and one of which is movable back and forth relatively to the other to place said stop in or out of unsheathed relation to said other part.

26. In combination, supporting structure, spaced instrumentalities holding a strand extended, one being movable relatively to the other to relax the strand, means to form a knot in the extended portion of the strand, and means to move the movable instrumentality to relax the strand while the knot is being formed therein.

27. A knot-tying mechanism including a rotary knot-tying means having its tying portion arranged to travel in, and projecting substantially lengthwise of, an orbit around the axis of rotation of said means, and means to hold the strand to be tied in position to be engaged by said portion while rotating.

28. A knot-tying mechanism including a knot-tying bill rotative in, and having its tying portion projecting substantially lengthwise of, an orbital path, and means to hold the strand to be tied in position to be engaged by said bill.

29. A knot-tying mechanism including a rotary knot-tying bill having a shank and a tying portion projecting angularly from the shank, said shank being eccentric of the axis of rotation of the bill, and means to hold the strand to be tied in position to be engaged by said bill.

30. A knot-tying mechanism including means to hold two strands with opposite bends therein and such bends close together, and knot-tying means movable in an orbit crossing both portions of each strand flanking its bend and into engagement with the strands while the latter are so held.

31. A knot-tying mechanism including means to hold two strands with opposite bends therein and such bends close together, and a knot-tying bill movable transversely of itself and in an orbit crossing both portions of each strand flanking its bend and into engagement with the strands while the latter are so held.

In testimony whereof I affix my signature.

FREDERICK KLEIN.
